(57) **CLAIM**

The ornamental design for packaging with surface ornamentation, as shown and described.

DESCRIPTION

The patent or application file contains at least one drawing executed in color. Copies of this patent or patent application publication with color drawing(s) will be provided by the Office upon request and payment of the necessary fee.

1.-6. Ornamentation for packaging

FIG. 1.1 is a front view of the packaging with surface ornamentation.

FIG. 1.2 is a front view of the packaging with surface ornamentation.

FIG. 1.3 is a front view of the packaging with surface ornamentation.

FIG. 1.4 is a front view of the packaging with surface ornamentation.

FIG. 1.5 is a front view of the packaging with surface ornamentation.

FIG. 1.6 is a front view of the packaging with surface ornamentation.

The broken lines in the figures illustrate the boundaries of the packaging, forming no part of the claimed design.
